UNITED STATES PATENT OFFICE.

SIDNEY B. DANE, OF LYNN, MASSACHUSETTS.

CLOTHES-DRYING MACHINE.

No. 873,777.

Specification of Letters Patent.

Patented Feb. 11, 1908.

Application filed December 6, 1906. Serial No. 346,533.

To all whom it may concern:

Be it known that I, SIDNEY B. DANE, a citizen of the United States, residing at Lynn, in the county of Essex and State of Massachusetts, have invented certain new and useful Improvements in Clothes-Drying Machines; and I do hereby declare the following to be a full, clear, and exact description of the invention, such as will enable others skilled in the art to which it appertains to make and use the same.

The present invention relates to clothes drying machines. It has become the practice in some localities to send to people's residences and get their week's wash in the morning of a certain day, to take it to the laundry, wash it, to put it through the extractor, and to return the clothes damp to the residence. This method has secured the complete segregation of each wash from every other wash, so that the clothes from one house are never confused with the clothes from another, nor is there any necessity for the tedious marking or sorting. Returning the clothes in a damp condition necessitates their immediate hanging out for drying, as, if they were to stand in a wet condition, they would become "sour" or possibly mildew. To eliminate, therefore, the necessity of drying clothes after their return to the residence, the applicant has produced a machine in which clothes may be rapidly dried so that they may be returned dry to the residence, and also in which a number of washes may be dried at one time and kept entirely separate from each other.

It should be noted that it is imperative, in order to do this work as economically as is demanded by trade conditions, that the drying be done with extreme expedition, as otherwise the cost of drying would be too great to permit of successful competition with the wet method. This requirement demands for its accomplishment the use of a large body of air and the loosening of the clothes, and the exposure thereof to such air, but subject to the limitation that the current of air must not be of sufficient force to hold the clothes suspended therein.

To the above end the present invention consists in the clothes drier hereinafter described and particularly defined in the claims.

In the accompanying drawings illustrating

the preferred form of the invention, Figure 1 is a side elevation, Fig. 2 is an elevation of the left end, while Fig. 3 is a transverse sectional elevation, and Fig. 4 is a longitudinal section of the drum.

The principal part of the apparatus is the drier proper, indicated generally by the reference character 1. A blower 2 drives a current of air through the drier 1, which air, before it enters the blower, is heated in the heater 3.

The heater consists of any convenient device for heating the air, and in the present embodiment comprises a box filled with steam pipes through which the air from out of doors passes to the blower 2, by which it is drawn through the heater and forced into the drier proper, 1. The blower is driven by a belt from a counter-shaft.

The drier 1 consists of a rotating drum 4, seen best in Fig. 4, which is mounted on trunnions 5 and 6. The cylindrical part of the drum 4 is made of wood. The right-hand end or head 7 of the drum is secured to the cylindrical portion. The other end of the drum is open. The air enters through the open end and passes out through the holes 8 in the head 7. The open end of the drum is closed by a stationary head 9 which is made of wood and provided on the right-hand side with a door 10, through which the operation of the apparatus may be observed. This head is provided with an opening 11 through which the heated air from the blower is discharged into the drum.

The drum is divided into a number of compartments, which are made by providing a series of wire screen diaphragms 12 which extend completely across the drum and separate it into a series of compartments, each of which is adapted to receive one wash. Tag holders 15 are provided which correspond in position to each compartment. These tag holders are clips secured upon the drum over each compartment, and when a wash is placed in a drum its tag is placed in the tag holder, then, when the wash is taken out, its tag is attached to the hamper in which it is placed. In the illustrated embodiment there are shown six such compartments, and for each two compartments a door 13 is provided which opens into the compartments. These doors are normally held closed by latches and form a

continuation of the cylindrical surface of the drum, so that the inner side of the drum is a continuous cylindrical surface except for a series of lifting boards 14 which project radially inward from the cylindrical wall. When the drum is rotated these lifting boards engage and lift the clothes up toward the top and allow them to fall from the top to the bottom through the current of air passing through the drum. The drum is rotated by means of a belt from a counter-shaft. In order to introduce the air into the drum in such a way as to cause it to flow from end to end thereof and to obtain the best results, it is introduced at one side of the center and on the rising side of the drum. Thus the air current through the drum enters the opening 11 and passes longitudinally through the drum and emerges through the openings 8 in the fixed head. It is necessary that the drum be of considerable size in order that the falling clothes will have a considerable distance to pass through the air and therefore the machine which the applicant has constructed is made with the drum about eight feet in diameter. It might be supposed that by decreasing the size of the drum and increasing the pressure of the air, an equal amount of air could be brought into contact with the clothes, but this is not so, for in such construction the current of air would be so strong that it would hold the clothes against the screen diaphragms and prevent their agitation and the exposure of all the clothes to the influence of the drying air. Therefore it is necessary that the drum be of such size with relation to the amount of air passing through it that the clothes will not be held against the screens by such current of air but will be permitted to fall through the current of air. This provides for the exposure of all the pieces of clothes to the drying action of the air. It should be understood, therefore, that the drum must be of such size with relation to the amount of air forced through it that the air will not hold the clothes against the diaphragms. The distribution of the holes in the fixed head of the drier causes a corresponding distribution of the air current within the drum.

The apparatus is used as follows: The drum being brought to rest with the doors 13 in the position illustrated in Fig. 1, the doors are opened and into each compartment a wash is placed. The wash is placed in this compartment just at it comes from the extractor, with the clothes still packed together as a result of the operation thereof, so that this apparatus not only serves to dry the clothes, but also serves to loosen them up and eliminate the use of the tumbler. Then the doors are closed and locked, the drum is set in motion, and the blower is started. In the course of a short time (with this apparatus about twenty minutes), the clothes are

quite dried, the blower is stopped, and the drum brought to rest, the doors are opened and the clothes are removed, each wash being kept by itself without confusion with others.

This invention is not limited to the construction illustrated and described herein, but may be embodied in other forms within the scope of the following claims:

1. A clothes drying machine having, in combination, a drum mounted to rotate upon a horizontal axis having one of its ends open, a stationary head located adjacent to the open end of the drum, and means for introducing a blast of air through the stationary head located in such position with relation to the direction of rotation of the drum that the air enters on the rising side of the drum so as to cause the air to pass across the path of motion of the falling clothes lifted up by the drum, substantially as described.

2. A clothes drying machine having, in combination, a drum mounted to rotate upon a horizontal axis provided upon its interior with means for lifting the clothes introduced into the drum and permitting them to fall from the top to the bottom thereof, and means for introducing a blast of air into the drum opposite the falling clothes, substantially as described.

3. A clothes drying machine having, in combination, a drum supported to rotate upon a horizontal axis provided with a series of screen diaphragms arranged transversely of the drum and separating it into a plurality of compartments, means for introducing a blast of air at one end of the drum, the periphery of the drum being provided with doors permitting access to the compartments, substantially as described.

4. A clothes drying machine having, in combination, a drum supported to rotate upon a horizontal axis, a plurality of screen diaphragms each of the full size of the inside of the drum and dividing it into separate compartments arranged transversely of the drum, the inside of the peripheral walls of the drum being provided with a plurality of lifting boards for lifting the clothes from the bottom of the drum and permitting them to fall through the air therein, and means for introducing a blast of air at one end of the drum and on the rising side of the drum, so that the falling clothes pass through the incoming blast of air, substantially as described.

5. A clothes drying machine having, in combination, a drum supported to rotate upon a horizontal axis and provided with a series of screen diaphragms dividing it into a plurality of compartments, the inner wall of the drum being provided in each compartment with lifting boards for lifting clothes up from the bottom of the drum, such lifting

boards in the different compartments being arranged in different angular positions so that each compartment drops its clothes at a different time from the adjacent compartment, and means for introducing a blast of air at one end of the drum on the rising side of the drum, substantially as described.

In testimony whereof I affix my signature, in presence of two witnesses.
